(57) **CLAIM**

The ornamental design for a window treatment, as shown
and described.

DESCRIPTION

FIG. 1 is a perspective view of a window treatment showing
our new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a perspective view of a second embodiment
thereof;

FIG. 9 is a front view thereof;

FIG. 10 is a rear view thereof;

FIG. 11 is a top view thereof;

FIG. 12 is a bottom view thereof;

FIG. 13 is a left side view thereof; and,

FIG. 14 is a right side view thereof.

The broken lines illustrate portions of the window treatment
that form no part of the claimed design.

The break lines shown in FIGS. 8-12 symbolize breaks
in the length of the article in which the claimed design is
embodied. The appearance of any portion of the article
between the break lines forms no part of the claimed design.
